(57) **CLAIM**

The ornamental design of the cover for a surface mount control box, as shown and described.

DESCRIPTION

FIG. 1 is a perspective view of the cover for a surface mount control box of the present invention.

FIG. 2 is a perspective view of the cover for a surface mount control box of FIG. 1 with the cover in a closed position;

FIG. 3 is a top view of the cover for a surface mount control box of FIG. 1 with the cover in a closed position;

FIG. 4 is a top view of the cover for a surface mount control box of FIG. 1;

FIG. 5 is a left side view of the cover for a surface mount control box of FIG. 1;

FIG. 6 is a right view of the cover for a surface mount control box of FIG. 1;

FIG. 7 is a front view of the cover for a surface mount control box of FIG. 1;

FIG. 8 is a back view of the cover for a surface mount control box of FIG. 1 with the cover in a closed position; and,

FIG. 9 is a bottom view of the cover for a surface mount control box of FIG. 1.

The broken line showing of structural features is included for the purpose of illustrating non-claimed subject matter and forms no part of the claimed design.
